UNITED STATES PATENT OFFICE

2,574,189

ETHERS OF POLYCHLORO DIPHENYL METHANE

David M. Musser, Fair Lawn, N. J., assignor to
Pacific Mills, Boston, Mass., a corporation of
Massachusetts

No. Drawing. Original application August 31,
1946, Serial No. 694,422. Divided and this ap-
plication December 23, 1950; Serial No. 202,570

4 Claims. (Cl. 260—613)

1

The present invention relates to new compositions of matter characterized by the desirable property of inhibiting the growth of bacteria and particularly useful as a textile finish, and to processes for preparing this composition. The present application is a division of my prior application Serial No. 694,422, filed August 31, 1946, now Patent No. 2,559,986, dated July 10, 1951.

Pathogenic germs are frequently present in or on the surface of textile fabrics, either as a result of contact of the fabric with the human body, as in the case of sheets, pillow cases, towels and the like, or as a result of exposure of the textile to an atmosphere in which such bacteria are present. These germs cling tenaciously to the textile fibers and may, under favorable moisture and temperature conditions, spread and grow colonies, which then present a serious danger of contamination. Means have long been sought for rendering a textile material permanently antagonistic or resistant to such bacteria so as to prevent their growth into colonies and to lessen the danger of contamination from contact with the textile material. It has been proposed to overcome this contamination hazard by applying to textile fabric a coating of a germicidal compound such as mercurial, a phenolic, or like compound. Such compounds are adequately bacteriostatic in this relationship, but the art heretofore has not succeeded in rendering textile materials permanently bacteriostatic by treatment with them. Fabrics coated with such materials commonly lose substantially all of their bacteriostatic property upon a single laundering and it is therefore necessary that the coating treatment be repeated each time the article is laundered. Such coating processes require considerable mechanical equipment and, therefore, are not a practicable procedure for use in most hotels, hospitals and private homes in which bed linens and towels are used.

It is an object of the present invention to provide improved bacteriostatic compounds and processes for making the same, suitable for use in finishing cellulosic materials such as textile fabrics, threads, yarns and fibers, to impart thereto improved bacteriostatic properties which will be retained more or less indefinitely.

The novel bacteriostatic and hydrophilic compounds of the present invention comprise derivatives of 2,2'-dihydroxy 3,5,6,3',5',6'-hexachlorodiphenylmethane having the general formula

wherein R represents one of the group of radicals comprising $-\text{CH}_2-\text{CHOH}-\text{CH}_2-\text{O}-\text{CH}_2\text{Cl}$, and

2

I have found that the desirable property of inhibiting the growth of bacteria may be imparted to cellulosic material by treatment of the material, involving chemical reaction, in which my novel bacteriostatic and hydrophilic compound is attached to the cellulose molecule at the hydrocarbon chain, represented by R in the above formula. The combination of bactericidal and hydrophilic groups employed in the present invention increases the affinity of the cellulose for water but without, however, causing it to reach a degree of solubility undesirable in textile materials. The resulting modified cellulosic materials provide a bacteriostatic environment which restricts the growth of bacteria thereon under all conditions of moisture and temperature.

The bacteriostatic and hydrophilic compounds of the present invention are formed by reacting one of the hydroxyl groups of the chlorinated hydroxy diphenyl methane represented by the formula

with chlorinated glycerine, paraformaldehyde and hydrochloric acid to provide thereon a hydroxylated hydrocarbon chain. In the finished cellulose product this hydrocarbon chain is attached to the cellulose molecule.

The following example, given by way of illustration and not of limitation of the invention, shows a practical method for the preparation of bacteriostatic and hydrophilic compounds suitable for use in finishing cellulosic textile material, and practical methods for finishing such material to provide cellulosic materials having improved bacteriostatic properties.

Example

2,2'-dihydroxy 3,5,6,3',5',6'-hexachlorodiphenylmethane is dissolved in ethyl alcohol and metallic sodium is added slowly to this solution in 50 molar equivalents (1 mol of Na to 1 mol of diphenylmethane) to form a sodium phenolate. The solution is heated to the boiling point and α -monochloroglycerine is added slowly in molar proportions, i. e., 1 mol of glycerine to 1 mol of diphenylmethane, with the formation of a sodium chloride precipitate. The alcoholic solution is recovered by filtration, and the alcohol evaporated or distilled off, leaving a residue having a melting point of 97° C. This residue is dissolved in benzene and then paraformaldehyde is added

to the solution in molar proportions (1 to 2 mols of paraformaldehyde to 1 mol of the compound). Gaseous hydrochloric acid is passed through the benzene solution until the paraformaldehyde is completely dissolved. The solution is then neutralized with pyridine, using litmus paper as an indicator.

The compound contained in the resulting solution may be applied to textile fabrics in any one of the three following ways, to form a cellulose derivative which is bacteriostatic.

(A) Cotton fabric is pretreated with a 5% to 10% solution of sodium acetate, and squeezed to about 100% pickup. The treated fabric is then impregnated with a 1% to 2% solution of the compound in benzene. The cloth is passed through squeeze rolls (about 80% to 100% pickup) and then heated to about 130-150° C.

(B) The neutralized benzene solution is evaporated on a water bath and the solid residue dispersed in warm water by stirring. The textile fabric to be treated is pretreated with sodium acetate as in (A) above, and then impregnated with the water dispersion. Thereafter the fabric is heated to 130-150° C.

(C) The neutralized benzene solution is evaporated and the solid residue dispersed in a warm water solution of 5% to 10% sodium acetate. The textile fabric is impregnated directly, without pretreatment, with the water dispersion, and the excess removed by squeezing to a pickup of about 100% and the fabric thereafter heated at 130-150° C. as before.

The fabrics resulting from the treatments of the foregoing examples exhibit very pronounced bacteriostatic properties and retain these properties, even after several commercial launderings.

It will be appreciated that the bacteriostatic compounds of the present invention are useful generally for application to materials of a cellulosic nature, either native or regenerated, on which there are free hydroxyl groups. Cellulosic textile materials, such as cotton and other natural products, may be treated in the form of fibers, threads, yarns, or in the piece, as a woven, braided, netted or knitted fabric. Such treatment involves a chemical reaction upon the cellulose molecule with the production of a new cellulosic substance. The bacteriostatic qualities of this substance are not impaired by washing, dyeing or other treatments usually encountered in the finishing or use of textile material.

The foregoing disclosure of preferred embodiments of my invention is made by way of illustration and not of limitation. It will be appreciated

that changes may be made therein by those skilled in the art without departure from my invention, as expressed in the following claims.

I claim:

5. 1. Hydrophilic and bacteriostatic compounds of the group having the general formula

wherein R represents one of the group of radicals consisting of $-\text{CH}_2-\text{CHOH}-\text{CH}_2-\text{O}-\text{CH}_2\text{Cl}$, and

20. 2. The method for the preparation of a derivative of chlorinated diphenyl methane which comprises reacting monochloroglycerine with 2,2'-dihydroxy 3,5,6,3',5',6'-hexachlorodiphenylmethane in the presence of metallic sodium and thereafter reacting with paraformaldehyde and gaseous hydrochloric acid.

25. 3. The hydrophilic and bacteriostatic compound represented by the formula

35. 4. The hydrophilic and bacteriostatic compound represented by the formula

DAVID M. MUSSER.
